TELEPHONE SYSTEM

Rudolph Frank Stehlík, Antwerp, Belgium, assignor to Associated Telephone and Telegraph Company, Chicago, Ill., a corporation of Delaware

Application October 19, 1938, Serial No. 235,719
In Great Britain November 3, 1937

11 Claims. (Cl. 179—16)

The present invention concerns improvements in or relating to automatic or semi-automatic telephone systems and has for its object the provision of arrangements whereby a series of impulses already used for setting up a connection may at the same time be stored and repeated for any required purpose.

According to the invention a mechanical impulse repeater is taken into use on the initiation 10 of a call and is adapted to respond to impulses dialled by the subscriber at the same time as such impulses are controlling the setting up of a connection. When the call has reached a certain stage it can be determined whether the mechanical 15 impulse repeater will be required and also whether it will be required to transmit some or all of the digits registered. With a mechanical impulse repeater of the kind described in the J. W. McClew and C. R. Woodland British Patent 458,095 granted March 4, 1937, it will be necessary to suppress those impulses which are not required as the mechanism must be allowed to move to an extent corresponding to such impulse.

The invention is applicable to alternative routing 20 and zone metering arrangements in which metering impulses are transmitted from relay equipment associated with an outgoing junction line and also for making a record of the called party's number, for instance, in recording by printing or punching on a tape or ticket the number 25 of the called party for the purpose of assessing the charge to be made to the calling party.

The invention will be better understood from the following description taken in conjunction 30 with the accompanying drawings comprising Figs. 1, 2 and 3 which show the invention as applied to an arrangement for alternative routing.

In the drawings Fig. 1 shows a trunking diagram for three exchanges A, B and C while Figs. 2 and 3 show the circuits of the selector repeater 35 and mechanical impulse repeater located at exchange A. Referring to Fig. 1 in exchange A the finder switches F are permanently connected with selector repeaters SR and the seizure of a selector repeater is effective automatically to take 40 into use a mechanical impulse repeater MIR with its associated group of control relays. Local calls are set up over certain of the first 8 levels of the selector repeater and 2nd group selectors are accessible over these levels. The 9th level is employed for setting up calls to exchange C and the 50 10th level for setting up calls to exchange B and in the present case it is assumed that the first 5 contacts in the 10th level have access to exchange B over direct junctions DJ and incoming selector

IS2. The remaining 5 contacts have access to exchange B via exchange C over the incoming selector IS at exchange C over the incoming selector IS at exchange C and the incoming selector IS1 at exchange B. 5

In the operation of the system a call from exchange A to exchange B will normally be set up over one of the direct junctions DJ, these junctions forming the preferred route. If however all the junctions are busy the connection is 10 set up over the alternative route via exchange C.

It will be understood that if the connection is set up over the alternative route one more digit 15 must be transmitted than if the call proceeds over the preferred route in order to effect the setting of the incoming selector IS at exchange C. The circuits of Fig. 2 shown an arrangement whereby this is possible.

Referring now to Figs. 2 and 3 when the line 20 finder finds the calling line, relay A will operate over the loop extended to the selector repeater and at contacts *a1* closes a circuit for relay B. In addition at contact *a2* relay A prepares the impulsive circuit for subsequent switches if the call is a local one. Relay B in operating at contact *b1* extends earth back to the line finder over the P conductor; at contact *b2* closes the circuit of the polarising winding of the back bridge relay D; at contact *b3* prepares the impulsive circuit to the vertical magnet and to the mechanical 25 impulse repeater, at contact *b4* prepares a test and operating circuit for the rotary switch RS over which the mechanical impulse repeater is associated with the selector repeater and at contact *b5* prepares an operating circuit for relay HB. 30

If the mechanical impulse repeater MIR, Fig. 3 is busy an earth potential will be present on the P wiper of the rotary switch RS and hence the magnet of the rotary switch RS, Fig. 2, will be energised over the following self-interrupting circuit: earth at contact *ic1*, armature *ib2* and front contacts, bank contact and wiper P of the rotary switch RS, contacts *ha6*, *ba*, *hb6*, interrupter contacts *rsm*, winding of magnet RSM to battery. The rotary switch is therefore stepped until an 45 idle mechanical impulse repeater is found, the idle condition being indicated by the absence of potential on the P wiper. In this case relay HB operates in series with the magnet RSM over the circuit: earth, rotary off normal contacts *NR1*, 50 contact *b5*, winding of relay HB, interrupter contacts *rsm* winding of magnet RSM to battery. The magnet does not however operate in this case owing to the high resistance of relay HB. Relay HB in operating at contacts *hb1* and *hb2* 55

- completes the impulsive circuit from the mechanical impulse repeater over the outgoing speaking conductors; at contact *hb3* transmits dial tone to the calling subscriber by induction 5 over a third winding of relay A; at contact *hb4* completes the impulsive circuit to the mechanical impulse repeater; at contact *hb5* places a shunt round contact *ha6* to provide a holding circuit for relay *IB* independent of relay HA; at contact 10 *hb6* completes a further point in the holding circuit for relay *IB*; at contact *hb7* closes a point in the release circuit of the mechanical impulse repeater; at contact *hb8* prepares a circuit for relay IC and at contact *hb9* completes a point 15 in its own holding circuit.

The calling subscriber now dials the required number and the impulses are repeated at contact *a1* to the vertical magnet VM in the selector repeater and also the impulsive magnet R, 20 Fig. 3, in the mechanical impulse repeater. Vertical off-normal contacts now operate and at contact *N1*, Fig. 2, open the dial tone circuit; at contacts *N2* prepare the circuit for relay E and at contacts *N3* prepare a point in the circuit of release magnet Z. In addition relay C is energised 25 on the receipt of the first impulse and remains energised for the whole of the impulse series. Relay C, at contact *c1* places a shunt across the energising winding of relay D; at contact *c2* completes a circuit for relay E and at contact *c3* completes the circuit for relay IC, Fig. 3. Relay IC upon energising at contact *ic1* completes a circuit for relay *IB*; at contact *ic2* operates relay IP and at contact *ic3* operates the marking magnet M in 30 the mechanical impulse repeater. The marking magnet M is thus maintained energised for the whole of the impulse series. Relay *IB* in operating at contact *ib1* energises the polarising winding of relay DA; at contact *ib2* closes a holding 35 circuit for itself independent of contact *ic1*; at contact *ib3* shunts contact *is2* and at contact *ib4* prepares a circuit for relay IS. Relay IP in operating at contact *ip1* extends earth to the back contact associated with the armature *ib2* in order 40 to provide an extra guard period for the repeater during release or if the subscriber should replace his receiver before the connection is completed; at contact *ip2* magnet CSM of the control switch 45 CS is energised but this switch is arranged to operate on the reverse drive principle and hence the wipers are not stepped until the magnet is de-energised.

The operation of the mechanical impulse repeater to receive and transmit the dialled impulses 50 is described in detail in the British patent referred to above, and the following brief description is given in order that the operation of the repeater in conjunction with the control relays and the selector repeater may be fully understood.

When the impulses energise the receiving magnet R, the off-normal contacts N of the mechanical impulse repeater are closed to prepare the circuit for relay BY, which circuit is maintained open at interrupter contacts *Mdm* of the marking magnet M which is maintained energised 55 throughout the reception of the impulse series. In addition at contact *ip3* relay IP completes a circuit for relay IS over; earth, contact *ip3*, lower winding of relay IS, contact *ib4*, winding of the 60 transmitting magnet S to battery. Relay IS operates over this circuit but the magnet S does not. Relay IS at contact *is3* short-circuits its upper winding so that it is rendered slow to release. Relays IP and IS now remain operated 65 until the end of the impulse series when relay C

in the selector repeater releases and at contact *c3* opens the circuit for relay IC. Relay IC at contact *ic3* opens the circuit of the marking magnet M which releases and at interrupter contacts *Mdm* closes a circuit for BY. Relay BY at contact *by1* prepares a further guarding circuit for the repeater and at contact *by2* short-circuits relay IP from earth at the off-normal contacts N over the displacable pin Z and reset pin Y. In addition at contact *by3* relay BY locks up independently of the interrupter contacts *Mdm*. Relay IP releases after a short period and at contact *ip2* opens the circuit of magnet CSM to permit the wiper of the control switch to advance its wiper one step and at contact *ip3* opens the circuit for relay IS 10 which also releases after a short period whereupon a circuit is closed for the transmitting magnet S over: earth, contacts *ip3*, *by4*, *is3* winding of magnet S to battery. The sending magnet S now operates and opens its interrupter contacts *Sdm* 15 whereupon relay IP again energises and opens the circuit of the magnet S at contact *ip3*. The impulses stored in the mechanical impulse repeater are now retransmitted over the impulse springs IPS.

It will be understood of course that the magnet S should only be operated for a short period and that the operation of relays IP and IS are for the purpose of providing a delay between the reception and retransmission of the impulse series.

It is also to be noted that the control switch CS makes one step for each impulse series for a purpose which will be explained later in the description.

Returning now to the operation of the selector repeater, relay E operates on the first vertical step over: earth contacts *b1*, *c2*, *ha5*, interrupter contacts *rm*, off normal contacts *N2*, winding of relay E to battery. Relay E at contact *e1* prepares a point in the energising circuit for the rotary magnet RM and at contact *e2* closes a holding circuit for itself independent of relay C. When relay C releases at the end of the first impulses series it closes the circuit for the rotary magnet as follows: earth, contact *b1*, spring controlled by armature *c2*, contact *e1*, winding of rotary magnet RM to battery. The rotary magnet now energises and rotates the wipers (not shown) on to the first bank contact. In addition at contact *rm* the rotary magnet opens the locking circuit for relay E which now releases and at contact *e1* opens the circuit for the rotary magnet which also releases.

If the line on which the wipers are now set is busy, earth potential will be present on the P conductor and the following circuit is again closed for relay E: earth on the P conductor, contact *ha3*, interrupter contact *rm*, off normal contact *N2* winding of relay E to battery. Relay E again operates and closes the circuit for the rotary magnet and this interaction between the relay and the magnet continues until an idle line is found. An idle line will have no potential applied to the P conductor so that no earth will be present to relay E.

However the following circuit is now effective: earth, contact *b1*, 11th step springs *S2*, winding of relay HA, interrupter contacts *rm*, vertical off normal contact *N2*, winding of relay E to battery. Relay HA only, operates over this circuit which was not effective previously since relay HA was shunted and at contacts *ha1* and *ha2* extends the connection to the next switch; at contact *ha3* extends earth on the P conductor back to the preceding switches; at contact *ha4* opens the

circuit for relay E and at contact *hb5* opens the original energising circuit for relay E and at contact *hb6* opens the short-circuit around contact *hb5*.

5 The above series of operations take place on any call whether for a local subscriber or for a distant subscriber. Discrimination between the two types of call is, however, effected by the level to which the selector repeater is raised in response to the first series of impulses. As pointed out above certain of the first 8 levels are allocated to local connections and the 9th and 10th levels are allocated to distant connections. When the selector repeater is raised to the 9th or 10th levels 10 normal post springs NP¹ and NP³ are opened while NP² is closed. On the levels over which local connections may be set up normal post springs NP¹ and NP³ remain closed while spring NP² remains open and hence on levels other than 15 the 9th or 10th i. e. on local calls, the locking circuit for relay HB is opened on the first rotary step of the selector repeater at rotary off normal contacts NR¹. Relay HB, therefore, de-energises 20 and at contacts *hb1* and *hb2* disconnects the outgoing conductors of the selector repeater from the mechanical impulse repeater and connects them to the loop extending from the calling subscriber. 25

At contact *hb4* relay HB opens the impulsive circuit to the mechanical impulse repeater and at contact *hb8* opens a further point in the circuit of relay IC. The mechanical impulse repeater is therefore released. Further on the first rotary step off-normal springs NR³ are closed and 30 a circuit is completed for the release magnet Z from earth at normal post springs NP³ whereupon the wipers of the selector repeater are restored to normal. The remaining impulses reset the selector repeater to a level at which openings NP¹ and NP³ are opened and control the 35 setting of the local switches in the usual way, the impulses being repeated at contact *a2*.

If however the call is for a distant exchange normal post springs NP² are operated and the 40 locking circuit of relay HB now extends from earth, at contact *hb9* over the normal post springs NP². In addition normal post springs NP¹ operate to remove earth from the metering conductor 45 since on a call to another exchange the charge 50 will be assessed separately.

It is now necessary to consider the difference in operation of the circuit when the call to exchange B is made over a direct junction and when it is made over the intermediate exchange C. 55 For this purpose it should be explained that for connections between exchange A and exchange B four digits are necessary, the first of which is always 9 and the remaining three are employed for setting the penultimate and final selectors in 60 exchange B.

Assuming first that the selector repeater seizes a direct junction to exchange B then this seizure takes place before the mechanical impulse repeater commences to retransmit the first digit 0, 65 the necessary delay being caused by the release of relays IP and IS as described above. When however the first digit is retransmitted at the impulse springs IPS it is rendered ineffective in this case since these springs are short circuited by 70 contact *da1* of relay DA.

When the second impulse series has been received by the mechanical impulse repeater however earth is extended over the wiper of the control switch CS to energise the lower winding of 75 relay DA. Relay DA now operates and removes

the short-circuit from around the impulsive springs and connects them to the outgoing conductors of the selector repeater. The second, third and fourth digits registered on the mechanical impulse repeater are therefore retransmitted 5 to set the switches in exchange B. When the four digits have been retransmitted the control switch steps to contact 6 whereupon earth is extended over contact *hb1* to shunt relay HB. Relay HB thereupon releases with the same results as 10 described above.

The junctions extending from exchange A to exchange C over which a call to exchange B is set up, when all the direct junctions are unavailable, have their connections reversed in the banks 15 of the selector repeater and hence as soon as one of these junctions is seized, relay DA operates with the same result as described above but in this case it operates before retransmission of any of the stored digits has taken place. All the four 20 impulses stored in the mechanical impulse repeater are therefore retransmitted and the first digit 0 serves to position the incoming selector IS in exchange C to the 10th level over which it has access to junctions leading to exchange B. The 25 mechanical impulse repeater is released after the retransmission of all the stored digits in the manner described above.

When the calling party replaces his receiver relay A releases, followed by relay B and a circuit 30 is then closed for the release magnet ZM as follows: earth, contacts *a1*, *b3*, vertical off-normal contact N³, winding of release magnet ZM to battery. Relay HA also releases and the selector repeater is therefore restored to normal. 35

A call from exchange A to exchange C will be set up in a similar manner to a call to exchange B over the preferred route except that in this case the first digit dialled is 9 instead of 0. The operation of the system however is in general so 40 similar in the two cases that no further description will be given. It will of course be understood that alternative routing facilities can also be applied to cases where the direct junctions between exchanges A and C are unavailable. In this case 45 the alternative route would extend through exchange B.

It will be understood that with a larger system it may be necessary to provide the selector repeater with two sets of wipers, local connections 50 being set up over one set and distant connections over the other. The connection of the wipers would be controlled by a wiper switching relay in accordance with the first digit and the switch would also retain the drop-back feature. 55

I claim:

1. In an automatic telephone system, a selector switch, a plurality of mechanical impulse repeaters, means individual to said switch effective when operated for automatically connecting an idle one 60 of said mechanical repeaters to said selector, means in said switch operated responsive to the seizure thereof by a calling subscriber for operating said first mentioned means, means in said switch operated responsive to the operative association of an idle one of said repeaters with said switch for signalling the calling subscriber, and means in said switch for controlling the setting of said switch in accordance with only the series of impulses of a first digit received from a calling subscriber and for setting said repeater in accordance with the series of impulses of all the digits received from a calling subscriber. 65

2. In an automatic telephone system, a selector switch, a plurality of mechanical impulse repeat- 75

- ers, means individual to said switch effective when operated for automatically connecting an idle one of said mechanical repeaters to said selector, means in said switch operated responsive to the seizure thereof by a calling subscriber for operating said first mentioned means, means in said switch operated responsive to the operative association of an idle one of said repeaters with said switch for signalling the calling subscriber, and means in said switch for simultaneously controlling the setting of said switch and the setting of said repeater in accordance with the series of impulses comprising the first digit dialled by a calling subscriber and for thereafter controlling the setting of said repeater in accordance with the series of impulses comprising each of the remaining digits dialled by a calling subscriber.
3. In an automatic telephone system, a selector switch, a mechanical impulse repeater associated therewith, means in said switch operated responsive to received series of impulses from a calling subscriber corresponding to the digits of a called subscriber's number, said selector switch operated to a certain position under control of said means in accordance with the series of impulses of a certain first digit, said repeater operated by said means in accordance with the series of impulses of all digits to register the same, means in said switch operated responsive to the positioning of said switch to said certain position for controlling said impulse repeater to cause the same to retransmit all the registered digits, and means in the repeater for rendering ineffective only the retransmitted series of impulses of the first registered digit.
4. In an automatic telephone system a first exchange, a mechanical impulse repeater at said second exchange, a selector switch at said exchange, a second exchange, trunk lines terminating in said second exchange accessible to said switch, a third exchange, preferred trunks terminating in said third exchange accessible to said switch, trunk lines interconnecting said second and said third exchange, means in said switch operated responsive to the seizure thereof by a calling subscriber and controlled by the series of impulses of each digit of a called number dialled by the calling subscriber, said means controlling said switch to select an idle preferred trunk line when the first digit dialled indicates that the called subscriber is located in said third exchange and controlling said impulse repeater to register all the digits of the called number, means in said switch effective when all of said preferred trunk lines are busy for causing said switch to select an idle trunk line to said second exchange, and means in said repeater operated responsive to the selection of an idle trunk line to said second exchange for controlling said repeater to retransmit series of impulses corresponding to all of the digits registered over said selected trunk line to said second exchange, means in said second exchange controlled by the impulses of the first digit retransmitted for selecting an idle trunk line interconnecting said second and said third exchanges, and switches at said third exchange controlled by the remaining retransmitted digits of the called number for connecting with the called subscriber.
5. In an automatic telephone system a first exchange, a selector and an impulse register at said first exchange, switching equipment at a second exchange, trunk lines extending to said second exchange, means in said switch controlled responsive to the reception of series of impulses correspond-

ing to the digits of a called subscriber's number transmitted by a calling subscriber for controlling said impulse register to thereby register all of said series of impulses, means in said switch operated by the series of impulses of the first digit for controlling the said switch to select an idle trunk line to said second exchange, means in said register operated responsive to the selection of an idle trunk line for rendering said register effective to retransmit all of the registered series of impulses over the selected trunk line, and means in said register for preventing the retransmitted series of impulses corresponding to the first digit from being transmitted over the selected trunk line and for permitting the remaining series of impulses corresponding to the remaining digits of the called number to be retransmitted over the trunk line, said remaining series of impulses controlling said switching equipment over said selected trunk line to complete a connection between a calling subscriber and a called subscriber.

6. In a telephone system, a first and a second exchange, a first group of trunk lines over which connections are completed between said exchanges, a second group of trunk lines over which connections are completed between said exchanges by way of a tandem exchange, a selector switch and an impulse register in said first exchange, a calling subscriber in said first exchange, means in said switch operated by impulses comprising a first digit dialled by said subscriber for controlling said switch to select an idle trunk line in said first group or said second group and for simultaneously controlling said register to register the impulses of the first digit, said means thereafter controlling said register to register the series of impulses corresponding to the remaining digits dialled by said subscriber, means in said register operated responsive to the seizure of an idle trunk line in either of said group for causing said register to start retransmitting impulses corresponding to the registered digits, and means in the register operated when the seized idle trunk line is in said first group for preventing retransmission of a first registered digit and permitting retransmission of remaining registered digits over said seized trunk line, said last mentioned means rendered ineffective when the seized idle trunk line is in said second group to permit the retransmission of all registered digits over said seized trunk line.

7. In an automatic telephone system, a selector switch, an impulse register, means for seizing said register to connect the same to said selector operated responsive to seizure of said selector by a calling subscriber, means for operating said selector responsive to first digits of called numbers to extend either local or outgoing calls and for operating said register to register said first digits, means in said switch operated when the first digit represents a local call for restoring the switch to normal and for disconnecting said register, means in said switch operated when the first digit represents a toll call for preventing said last mentioned means from becoming effective and for controlling said register to retransmit the registered first digit.

8. In an automatic telephone system comprising a first and second exchange interconnected by trunk lines, a selector and an impulse register in said first exchange, means for simultaneously operating said selector and said register during the establishment of a connection to a called subscriber in either exchange, means for releasing

5 said register when the call is for a subscriber in said first exchange and for preventing the release thereof when the call is for a subscriber in the second exchange, and means in said register effective when the call is for said second exchange for transmitting series of impulses over the interconnected trunk line to set the switching equipment in the second exchange.

9. In an automatic telephone system, a selector having directive primary movement and automatic secondary movement, a set of wipers positioned by said two movements, an impulse register, an outgoing impulsive circuit for said register, means operated responsive to the seizure of said selector by a calling subscriber for operatively associating said register with said selector, means in said selector operated responsive to the operative association of said selector and said register for connecting said outgoing impulsive circuit to said set of wipers, means in said switch operated responsive to a first digit transmitted by a calling

subscriber for controlling the directive primary movement and for controlling said register to register the said digit, said automatic secondary movement thereafter effective to control said wipers, and means in said register effective upon the termination of the automatic secondary movement for controlling said outgoing impulse circuit to retransmit the registered digit over said set of wipers.

10. A telephone system as claimed in claim 3 wherein the impulses retransmitted by said repeater are transmitted over said selector switch.

11. A system as claimed in claim 3 wherein the mechanical impulse repeater is one of a plurality of such switches, and a rotary switch individual to said selector and controlled thereby is automatically controlled to search for and connect an idle one of said repeater to the selector when same is seized.

RUDOLPH FRANK STEHLIK. 20
